UNITED STATES PATENT OFFICE.

SAMUEL B. FIELD, OF HOLBROOK, MASSACHUSETTS, ASSIGNOR, BY MESNE ASSIGNMENTS, TO STATE STREET TRUST COMPANY, TRUSTEE, A CORPORATION OF MASSACHUSETTS.

CAN-CAPPING MACHINE.

Application filed May 29, 1920. Serial No. 385,245.

To all whom it may concern:

Be it known that I, SAMUEL B. FIELD, a citizen of the United States, residing at Holbrook, county of Norfolk, Commonwealth of Massachusetts, have invented certain new and useful Improvements in Can-Capping Machines, of which the following is a specification.

This invention relates to can capping machines and particularly to a machine for placing the cap or upper end on a filled container. As illustrative of my invention I shall show and herein specifically describe a machine especially adapted for lodging a metallic top on a fibre or metal container body for the purpose of completing the package. While my invention is not to be construed as limited to the particular container or type of container or top or cover, I nevertheless find it convenient to refer rather specifically to this type of container and cover inasmuch as it well illustrates the advantages of my invention and at the same time constitutes a practical and useful embodiment well adapted to fill a very considerable demand in the trade in which this type of container is employed.

The drawings herewith are therefore to be understood as illustrative in so far as the broader features of my invention are concerned, while also involving many practical details of more specific nature. In these drawings as well as throughout the specification like reference characters are employed to indicate corresponding parts. In the drawings:—

Fig. I is a side elevation of such a machine in accordance with my invention.

Fig. II is an end elevation partly in section viewed from the right of Fig. I.

Fig. III is a detailed fragmentary plan view showing the can separating mechanism.

Fig. IV is a similar view of the cover or top separating mechanism.

Fig. V is a side elevation partly in section of the cover or lid carrier in lid receiving position.

Fig. VI is a similar view with the parts in lid delivering position.

Fig. VII is a side view of the lid applying mechanism.

Fig. VIII is a view of can and lid in position of initial assembly.

Fig. IX is a plan view of the cover placing die, 55

Figs. X and XI are diagrammatic views showing successive stages in the transfer of the cans through the machine,

Fig. XII is a partial plan view of my 60 machine, and Fig. XIII is a detail view of the cover delivery mechanism.

My machine consists of a base 1, on which a bed 2 is supported by vertical frame pieces 3. Across the upper part of the machine is 65 an arched frame or bridge 4 extending longitudinally of the machine. The main power shaft, driven from any suitable source, is indicated at 5 and has a hand wheel 6. The shaft 5 has a pinion 7 meshing 70 with a gear 8 on a counter shaft 9. From the counter shaft 9 a longitudinal shaft 10 is driven by a pair of bevel pinions 11. The shaft 10 has a spur gear 10' thereon which meshes with a similar gear on a stub shaft 10^a (immediately behind the shaft 10 in Fig. I). The stub shaft 10^a through a pair of bevel pinions 12 drives a vertical shaft 13 at the intake end of the machine. The shaft 13 is splined within a hollow shaft 14 which carries a cam 15 for operating the lid carrier, as will appear hereinafter. The shaft 14 is mounted in a bracket 16 which forms part of a head 17 which is vertically adjustable by a screw 18 in a slideway 19. 75 Slidable longitudinally along the bed 2 is a crosshead 20. On each side of the cross-head 20 are heads 21 which are provided with transverse ways in which slide can die-carriers 22 retained in said ways by gibbs 23. To the heads 24 of the slides or die-carriers 22 are attached upper and lower can embracing plates or dies 25. Between the spaced heads 21 lies the can way 30 which 80 extends longitudinally of the machine and on which the bottoms of the cans C rest as they are moved through the machine from left to right as shown in Fig. I. The cans are fed to the way 30 by an endless conveyor 31 which runs over a pulley 32 driven by chain and sprocket 33 from a counter shaft 33' carrying the bevel pinion 34 which meshes with the pinion 35 on the shaft 10. At the opposite end of the machine the filled 85 cans are removed on any suitable conveyor as 36 running over a pulley 37 to a suitable point of delivery not shown.

Referring now to the cap die group which 90

100

105

is mounted on the slidable crosshead 20 it will be seen that the heads 21 each support a vertical bracket 26 which is slotted at 27 to adjustably receive the horizontal pivot 28 of the cover dies 40. The general structure of the dies 40 is detailed in Figs. VI, VII and IX. The dies 40 consist of duplicate members having recess-defining portions 41 which are normally open to receive the cap 10 and are adapted to be closed by the operation of the can embracing plates or can dies 25 to clamp the cap therein. The cap dies are maintained in alinement by sliding plates 41^a which interlock each with its die 15 when the dies are brought together. Fast to the underface of the cap dies is a cap-retaining plate 41^b having a can-receiving opening therein of slightly smaller diameter than the cap-receiving opening of the cap dies and 20 through which the can is adapted to extend to receive the cap. The edges of said can-receiving opening are beveled to guide the can thereinto, and the plate retains the cap within the cap dies.

25 On the other side of its pivot each die 40 is provided with a stop arm 43 adapted to contact with an adjustable screw 44 to arrest the die in its down position. In its upward position an adjustable screw stop 45 30 is disposed to contact with the die 40 to determine its correct angular position when the slide is to the left and the die is receiving the cap from the cap delivery, as shown in Fig. VI. The die carries on its upper face a socketed block 47 covered by a plate 48 within which a ball 49 has bearing. The ball 49 is on the end of a stem 50 which is shouldered at 51 to give backing to the spring 52. This spring is contained within a case 53, the inner end of which is closed by a cap 54. This cup-shaped sleeve 53 is 35 slidable within a link 55, being held in a downward position by a spring 56 which is coiled about a stem 57. The lower end of the spring 56 bears on the upper end of the cup 53 and the upper end of said spring is received in an adjustable cup 58 which is tapped into the axial bore of the link 55 and is provided with a hexagon end 59 whereby it may be conveniently adjusted. The upper end of the stem 57 is provided 40 with an adjustable stop 60 working within an opening 61. The link 55 is also open at 55' to expose the hexagon end 59 of the cup 58. At its upper end the link is pivoted at 62 to a bracket 63 formed on a plate 64. The plate is adjustable in ways 65 by a screw 66 having a hand wheel 67. This adjustment by the hand wheel permits the regulation of the link 55 whenever the pivots of the dies 40 need to be adjusted in the vertical bracket 26. This adjustment is made where the machine is to be set for cans of a different height from those on which it has 65 been operating.

Extending from one of the brackets 26 is a longitudinally disposed rod 70 having depending clamps within which is fastened a pair of horizontally extending fingers 71 set between the ends of the rod and a single horizontally extending finger 72 which appears adjacent the left end of the rod in Fig. I. The rod 70 and the fingers 71 and 72 constitute a step by step can feed through the machine. A can C delivered to the point C' shown in Fig. I by the conveyor 31 is picked up by the finger 72 and moved to the position occupied by the can C². In this position it is picked up by the fingers 71 and moved to the position indicated by the can C³. In this position the can is initially engaged by the can dies 25 and moved to the position C⁴ at which point the cap or top is finally lodged in place. In this position the can is abandoned by the can dies 25 upon the retreat of the heads 23 but is picked up by the finger 73 and moved out to the position C⁵ from which it is crowded by succeeding cans until it is pushed on to the endless apron 36 and thus carried away from the machine.

The particular can separating or escapement mechanism for controlling the feed of the cans C along the conveyor 31 and for insuring that a can will always be in position to be picked up by the finger 72 is detailed in Fig. III. This mechanism consists of a pair of escapement fingers 400 and 420 disposed one in advance of the other transversely of the conveyor for operation by the vertical cam shaft 14. Fast on said shaft is a cam 401 adapted to contact the roll-provided end 401' of a lever 402 which is pivoted at 403 and is under spring control as indicated at 404. Fast to the lever 402 is a pair of links 405, 409. The link 405 is adjustably connected by the coupling 407 with a link 414 to which the escapement finger 420 is attached. The link 409 is loosely guided in a pair of spaced couplings 423, 424 between which is a spring 421, confined about said link. The spring 421 abuts the coupling 423 at one end and at its opposite end bears against a collar 421' fast on the link 409. Fast to the couplings 423, 424 is a link 406 which is connected to one end of a rocker 410 pivoted between its ends at 411, and connected at its other end to a link 412. The link 412 is adjustably connected by a link 413 to the escapement finger 400.

In the position of the parts illustrated in Fig. III, the finger 400 is represented as advanced in the path of the cans, and the finger 420 is withdrawn to allow the can which has passed finger 400 to feed to the pick-up finger 72. In the return movement of the lever 402, the position of the fingers will be reversed, that is, the finger 400 will be withdrawn from the path of the cans and

the finger 420 advanced into the can path.

In the event of a can being improperly placed, the light spring 421 will yield if the can were in position to prevent advance 5 of the finger 400, and the heavy spring 404 will yield if the can were in position to prevent advance of the finger 420, thus preventing jamming of the mechanism.

The tops of the cans are brought to the 10 machine on an endless conveyor 80 set at an incline where they are separated by one or the other of a pair of fingers 81—82 which are operated by an escapement for the details of which reference may be had 15 to Fig. IV. The finger 81 is continuously operated by a cam 83 on the upper end of the hollow shaft 14. The cam 83 works a lever 84 pivoted at 85 and normally held down by a spring 86. The lever 84 is connected 20 by a pair of wire links 87 and 88 to the finger 81, and the two links being adjustably connected by a coupling 89. The finger 81 is therefore continuously operated so that the conveyor 80 will always have a 25 cap in position against the finger 82.

In accordance with my invention the cap is only to be supplied in case its corresponding can is progressing properly through the machine to meet it. The cap positioned 30 against the stop 82 will be placed upon a can in the position of the can C³ shown in Fig. I. I therefore operate my cover release by the can itself in its movement to the position occupied by the can C³ in the drawing. This operation is effected by a lever 100 disposed across the path of the can and just beneath the guide rails 130 which parallel the supporting way 30. The lever 100 is pivoted at 101 and normally held across 40 the way by a spring 102. At its opposite end the spring 102 is connected by a link 103 to an arm 104 on the vertical shaft 105. This vertical shaft runs up at the left hand end of the machine as viewed in Fig. I 45 and has at its upper end a second short arm 106 which is connected by links 107—108 to the finger 82. The links 107—108 are connected by an adjustable block 109 by which the length of the throw of the finger 82 may 50 be regulated.

The can dies 25 set in the slides 22 are operated by levers 140. These levers are disposed on each side of the machine and have extended tops 141 grooved to receive 55 a spherical roller 142 set on a stud through the tail of each slide 22.

The lever 140 is pivoted at 143. Extending from the pivot 143 is a cam lever 140' terminating in a roller 144 which travels in 60 the cam groove 145 of a cam 146. This cam is mounted on the shaft 10. Pivoted in a fixed bracket at 147' is a link 147 which is connected at its opposite end to a yoke 148. The yoke 148 is pivoted at 148' in a boss on 65 the cam lever 140' and is operated thereby.

An elbow 149 extends from each of the levers 140 terminating in a foot 149'. This foot has a rounded bearing which rests on the flattened upper surface of the yoke 148. The yoke 148 is therefore given a vertical reciprocation, being held in substantial verticality by the link 147, to which it is attached at its upper end. In the yoke 148 is a pair of stems 150 extending up through the rounded bearings 149'. A spring 151 is arranged on each one of these stems, and the spring is compressed by a nut so that the arms 149 may yield slightly in case the can dies 25 meet any obstruction. In case of obstruction the arms 149 simply compress 80 the springs 151 permitting a yield without breaking or jamming the parts.

The entire capping head set on the cross-head 20 as heretofore explained is reciprocated on the bed 2. The levers 140 are stationary but this movement is permitted by the longitudinal slotting of the upper ends of the levers 140 which permits the travel of the rollers 142. This is necessary as the opening and closing of the can dies 25 90 takes place during the longitudinal movement of the head as a whole. The longitudinal travel of the carriage on the cross-head 20 is effected by a lever 160 pivoted at 161 and suitably linked to the crosshead 95 at 162. The lever is operated by a roll 163 engaging in a cam slot 164 in the cam 165.

My machine is provided with any suitable power control. In Fig. II I have indicated at 170 a power pulley on the shaft 5 100 and clutch members 171—172 operated by a lever 173 pivoted at its lower end in a bracket 174. The lever is operated by a push and pull rod 175, the handle 176 of which is shown at the left of Fig. II as being conveniently positioned for the operator of the machine.

During the motion of the crosshead along the machine, the cover receiving dies 40 are raised by the link 55. The raising of the dies 40 is so timed that the dies reach the proper angle just as they come under the end of the cover delivery chute 180.

Referring particularly to Figs. V and VI it will be seen that the chute 180 has a bottom plate 182 down which the covers slide 115 into the block 183 by which they are so guided as to drop on the head 184 of an arm 185. The head 184 constitutes a lid carrier and has a finger 184' which aids in holding 120 and positioning the cover or top T.

The lid carrier 184 is detachably mounted upon the arm 185 so as to automatically disengage from said arm in the event that a lid should be misplaced in the die 40 in such a way as to grip on the lid carrier 184 and not release therefrom when the die starts its motion. To this end the lid carrier is sleeved about the free end of the arm 185 125 and is normally positioned thereon by a 130

spring 185' attached thereto and to the arm, whereby when a lid is misplaced, the lid carrier will be pulled free of the arm. The machine will then be stopped and the lid carrier replaced by hand before further caps may be fed. The lid is held on the lid carrier 184 by a light blade spring 181 fastened to the block 183 and bearing at its free end against the lid, the lid dies being longitudinally slotted as indicated at 41² to accommodate said spring 181.

The arm 185 is pivoted at 186 and has at its opposite end a roller 187. This roller 187 is adapted for contact with a cam block 188 adjustably mounted in a short arm 190 which is pivoted at 191 to a bracket 192. A spring 193¹ is interposed between this arm and the bracket to normally hold the block away from the roller 187. The arm 190 is connected by a link 193 to a bell crank lever 194 the short arm of which has a roller 195 working in the cam 15. The return movement of the arm 190 is limited by contact of a stop projection 190' thereon, with a stop screw 190^a. The lever 194 is held retracted by a spring 196 to take up wear or lost motion in the cam 15. The normal position of the arm 185 is that shown in Fig. V, wherein it is in position to receive any cap or top coming down the slide 180.

The cam 15 is so timed that the arm 185 will be thrust forward just as the top dies 40 come into the position shown in Fig. V. This forward movement is made possible by mounting the arm 185 and bracket 192 on a slide 200 working in a slideway 201 on a bracket 202 on the vertically adjustable plate 19. This adjustment permits the positioning of the end of the chute 180 at the proper level to accommodate the dies 40 in any position of the vertical adjustment of their pivot in the brackets 26. The arm 185 is held from falling by a spring 285 Fig. XIII thereon engaging in a groove 286 formed in a block 287 fast to the slide 200. To further accommodate this adjustment the conveyor 80 is pivoted at 210 to the stud on which the upper pulley of the cap or top conveyor 80 is journaled. In any position of adjustment of the chute 180, therefore, movement of the bell crank lever 194 thrusts forward the slide 200 to the limit of its movement, as determined by the contact of a stop 200' on said slide 200 with a fixed stop 213 on the bracket. The slide 200 pauses at this phase of its travel just long enough for the cap dies 40 to close and grip the cap T, the continued movement of the lever 194 rocking the arm 190 to bring the cam 188 into contact with the roll 187, thereby raising the rear end of the arm 185 and withdrawing the lid carrier 185' from the cap die.

The bell crank 194 then returns, retracting the slide 200, and as the roller 187 comes 65 under the cam 187', the head 184 is again

brought up into the position shown in Fig. V whereupon another cover T is released by the stop 82 and dropped down the chute 180 to find its place on the head 184.

In order to prevent movement of the crosshead 20 during the motion of gripping the can and the lid in their respective positions, I provide an automatically releasable lock for the cross-head. The crosshead has a cam surface 300 along its under face terminating in a locking recess 301 into which is adapted to engage a stud 302 on the free end of a lever 303 pivoted at 304 in a bracket 305 and under spring control as at 306. The bracket 305 projects from the bed 2 of the machine. Pivoted at 308 to the bracket 305 is a bell crank lever 307 which is adapted to contact with a pin 307^a on one of the rockers 140 and has an arm 307', Fig. XII, engaged with the lever 303. When the rockers 140 separate the pin 307^a allows the spring 306 to swing the bell crank 307 outwardly on its pivot, thereby carrying the arm 307' upwardly and raising the lever 303 so that the roll 302 thereon will drop into the locking recess 301 of the cross head as said cross head moves to the left in Fig. I. The roll is released from the recess 301 by the inward or closing movement of the rockers 140 while the cross head is still positioned to the left in Fig. I. In such release the pin 307^a contacts the upper arm of the bell crank lever 307 when the rockers 140 swing inwardly and the bell crank is swung inwardly on its pivot, carrying the arm 307' thereof downwardly and thereby rocking the lever 303 downwardly to withdraw the roll 302 from the recess 301.

The cans advancing along the conveyor 31 from left to right of the machine, Fig. I, are separated by the can escapement fingers 400, 420 operated by the cam 401 and associated mechanism detailed in Fig. III, and the caps advancing along the conveyor 80 are separated by the cap escapement fingers 81, 82 operated by the cam 83 and associated mechanism detailed in Fig. IV.

The cap feed is so related to the feed of the cans through the machine that a cap will not be supplied unless its corresponding can is progressing properly through the machine to meet it at the point of cap lodgment, the point C⁴ in Fig. I. To this end the lever 100 is interposed in the path of the cans moving along the can way 30 and upon actuation by a can momentarily withdraws the cap release finger 82 from the path of the cap to allow a cap to enter the cap chute 180.

As the cap slides down the chute 180 it is guided to drop on the head 184 of the cap feed arm 185 which is thrust forward by the cam 15 and lever 194 just as the cap dies 40 swing into the cap receiving position shown in Fig. V.

As the crosshead 20 begins its rearward travel under the drive of the cam 165, the rockers 140 are swung outwardly by their cam 146, and the can die slides 22, which are actuated by the rollers 142 to said rockers, are drawn outwardly, thus opening the can dies 25. The separating travel of the slides 22 swings the links 55 slightly outwardly on their pivots, the movement being taken up by the springs 56. It also moves the rod 70 outwardly to withdraw the can feed fingers 72, 71, 73 thereof from the can way 30 in the continued rearward travel of the crosshead, the cap die is lifted by the links 55 which swing laterally about their pivots to bring the cap dies 40 into the cap receiving position relative to the cap-feed arm 185 shown in Fig. VI. At the end of the rearward movement of the crosshead the rockers 140 swing inwardly to close the can dies 25 about a can disposed in the position C³ in Fig. XI. The cap dies 40 are simultaneously closed and the can feed rod 70 moved inwardly to advance its fingers 72, 71, and 73 between the cans on the can way 30.

The can dies, cap dies and rod 70 then start forward, whereupon the finger 72 picks up a can at the point C' and moves it to the point C² Fig. X. The can which occupied the point C², Fig. X, is picked up by the fingers 71, 71 and moved to the point C³, and the can which occupied the point C³, Fig. X, is moved by the can dies 25 to the point C⁴, Fig. X, which point is the point of lodgment of the cap (see Fig. VII). The capped can which formerly occupied the point C⁴, Fig. X, and which was released when the can dies opened and the crosshead started its rearward movement, is picked up by the finger 73 and moved to the point C⁵, Fig. X, from which point it is crowded by succeeding cans onto the discharge conveyor 36 in the next operation of the crosshead, as indicated at C⁶, Fig. XI. The combinative action of these several mechanisms secures certain and accurate placement of the cap. As shown in Fig. VIII, the cap is initially applied to one corner of the can mouth and is progressively and continuously worked across the can mouth toward the opposite corner until snugly seated entirely over the can mouth.

What I therefore claim and desire to secure by Letters Patent is:

1. In combination, a can passageway, a pair of can dies movable towards and from each other to grip and release a can disposed therebetween, a pair of oppositely disposed cap dies mounted independently of said can dies and movable towards each other to close about and positively clamp a cap therebetween and movable away from each other to open and discharge said cap onto a can held between said can dies, and operative connections between said can dies

and said cap dies for causing the cap dies to follow the movement of the can dies.

2. In combination, a can passageway, a pair of can dies movable towards and from each other to grip and release a can disposed therebetween, a pair of oppositely disposed cap dies mounted independently of said dies and slidable towards each other to close about and positively clamp a cap therebetween and slidable away from each other to open and discharge said cap onto a can held between said can dies, and pivoted connections between said can dies and said cap dies for causing the cap dies to follow the movement of the can dies.

3. In combination, a can passageway, a pair of can dies movable towards and from each other to grip and release a can disposed therebetween, a pair of oppositely disposed cap dies mounted independently of said can dies and having complementary recess-defining portions effective when the dies are closed to encircle and positively clamp a cap therebetween and effective when the dies are opened to discharge said cap onto a can held between said can dies, and operative connections between said can dies and said cap dies for causing the cap dies to follow the movement of the can dies.

4. In combination, a can passageway, a pair of can dies mounted for longitudinal and transverse sliding movement relative to said way, and a pair of cap dies pivotally connected to said can dies to follow the movements thereof.

5. In combination, a can passageway, a can feed mechanism, a pair of oppositely movable can dies, a pair of oppositely disposed cap dies mounted independently of said can dies and movable towards and from each other and effective when closed to provide a recess within which a cap is adapted to be lodged and effective when opened to discharge said cap onto a can held by said can dies, and operative connections from said can dies to said cap dies and can feed mechanism for causing the cap dies and can feed mechanism to follow the movement of the can dies.

6. In combination, a can passageway, a pair of can dies movable longitudinally and transversely of the can passageway, and a pair of cap dies and a can feed mechanism operatively connected to said can dies to follow the movements thereof, said cap dies being pivotally mounted upon said can dies.

7. In combination, a longitudinally slidable crosshead, a can passageway, a can die mounted on said crosshead on each side of said passageway and having an opening and closing movement in a path transverse to the direction of travel of the cans, means operatively connected to said dies for effecting said opening and closing movements thereof, and a pair of cap dies pivotally

6
mounted upon said can dies for movement longitudinally and transversely of the can passageway.

8. In combination, a longitudinally slidable crosshead, a can passageway, a can die mounted on said crosshead on each side of said passageway and having an opening and closing movement in a path transverse to the direction of travel of the cans, a pair of rockers operatively connected to said dies for effecting said opening and closing movements thereof during the reciprocation of the crosshead, and a pair of cap dies pivotally mounted upon said can dies for movement longitudinally and transversely of the can passageway.

9. In combination, a can passageway, a crosshead slidable longitudinally relative thereto, a can die mounted on said crosshead on either side of said passageway and slidable transversely towards and from said passageway, a rocker for sliding each can die transversely, and a drive for said rockers comprising a drive shaft, a cam thereon, and a cam lever operated by said cam and connected with said rockers.

10. In combination, a can passageway, a crosshead slidable longitudinally relative thereto, a can die mounted on said crosshead on either side of said passageway and slidable transversely towards and from said passageway, a rocker for sliding each can die transversely, a drive for said rockers comprising a drive shaft, a cam thereon, a cam lever operated by said cam, a yoke pivoted to said lever and engaging said rockers, and a connection permitting said rockers yielding movement in a vertical plane.

11. In combination, a can passageway, a crosshead slidable longitudinally relative thereto, a can die mounted on said crosshead on either side of said passageway and slidable transversely towards and from said passageway, a rocker for sliding each can die transversely, a drive for said rockers comprising a drive shaft, a cam thereon, a cam lever operated by said cam and connected with said rockers, and a drive for said crosshead including a second cam on said drive shaft, and an operative connection from said second-named cam to said crosshead.

12. In combination, a can passageway, a can feed mechanism comprising a rod mounted for longitudinal sliding movement relative to said passageway, and for movement towards and from said passageway, and an actuating mechanism for said rod comprising a pair of can dies slidable longitudinally and transversely.

13. In combination, a can passageway, a can feed mechanism comprising a finger rod disposed parallel to said passageway and having longitudinal and engaging and dis-

engaging movement relative thereto, and an actuating mechanism for said rod comprising a pair of can dies slidable longitudinally and transversely, rockers for sliding said dies transversely, and a longitudinally slidable cross head carrying said dies.

14. In combination, a can passageway, and a can feed mechanism for intermittently advancing the cans along said passageway, comprising a rod mounted in offset relation to said passageway and provided with a can feed finger adapted to be advanced between a pair of adjacent cans on said passageway, and means for moving said rod into and out of effective feeding relation to the cans and for reciprocating said rod.

15. In combination, a can passageway, and a can feed mechanism for intermittently advancing the cans along said passageway, comprising a rod mounted in offset relation to said passageway and provided with a can feed finger adapted to be advanced between a pair of adjacent cans on said passageway, a longitudinally slidable crosshead and means carried by said crosshead and slidable transversely and operatively connected with said rod for moving said rod into and out of effective feeding relation to the cans and for reciprocating said rod.

16. In combination, a can passageway, a can delivery thereto, a cap delivery, a pair of can dies movable longitudinally and transversely of the can passageway, a pair of cap dies and a can feed mechanism operatively connected to said can dies to follow the movements thereof and a cap release mechanism controlling the delivery of caps to said cap dies and operated by and in the feed of the cans along said can passageway.

17. In combination, a can passageway, a can delivery thereto, a cap delivery, a pair of can dies movable relative to the can passageway, a pair of cap dies and a can feed mechanism operatively connected to said can dies to follow the movements thereof, and a cap release mechanism controlling the delivery of caps to said cap dies and operated by and in the feed of the cans along said can passageway.

18. In combination, a longitudinally extending drive shaft, a vertically disposed cam shaft operated therefrom, a crosshead reciprocated from said drive shaft, a pair of can dies mounted on said crosshead, a pair of rockers driven from said drive shaft and operatively connected with said dies for opening and closing the same, a can feed mechanism, and a pair of cap dies mounted to follow the movements of said can dies, a cap feed mechanism, a cap separating mechanism including a cap release finger operated by the movement of the cans, and a can separating mechanism operated by said vertically disposed shaft.

19. In combination, a reciprocating cross-

head, a drive shaft therefor, a pair of can dies mounted on said crosshead, means driven from said drive shaft and operatively connected with said dies for opening and

5 closing the same, a can feed mechanism, a cap feed mechanism, a cap separating mechanism including a cap release finger operated by the movement of the cans and a pair of cap dies operatively connected to said

10 can dies.

20. In combination, a longitudinally extending drive shaft, a vertically disposed cam shaft operated therefrom, a crosshead reciprocated from said drive shaft, a pair

15 of can dies mounted on said crosshead, a can feed mechanism, a cap feed mechanism, a cap separating mechanism including a cap release finger operated by the movement of the cans, a can separating mechanism oper-

20 ated by said vertically disposed cam shaft, and a pair of cap dies operatively connected with said can dies.

21. In combination, a can passageway, a cap delivery, a cap separating mechanism comprising a check finger and a release finger adapted to be entered into and withdrawn from the path of the caps, an actuating mechanism for said cap check finger including a cam shaft, a cam thereon, a cam lever, and an operative connection from said lever to one of said fingers, and a can actuated operating connection for said cap release finger comprising a lever disposed in the path of the cans for actuation thereby, and an operative connection from said lever to said cap release finger.

22. In combination, a can passageway, a can delivery, a can separating mechanism, a cap delivery, a pair of cap separating fingers, a cam shaft, an operative connection from said shaft to one of said fingers, a can operated connection to the other of said fingers, and an operative connection from said cam shaft to said can separating mechanism.

23. In combination, a can passageway, a can delivery thereto, and a can separating mechanism comprising a pair of spaced fingers adapted to be alternately entered into and withdrawn from the path of the cans, and an actuating mechanism therefor comprising a cam shaft, a cam thereon, a lever actuated by said cam, and a system of links from said lever to said fingers, including a rocker pivoted between its ends and an interposed spring.

24. In combination, a cap chute, a cap feed arm pivotally and slidably mounted relative thereto, means to slide said arm, and means actuated by said first-named means effective during the travel of the arm to rock said arm on its pivot.

25. In combination, a cap chute, a cap feed arm pivotally and slidably mounted relative thereto, means to slide said arm, and a cam

block actuated by said first-named means effective during the travel of the arm to rock said arm on its pivot.

26. In combination, a cap chute, a slide mounted adjacent thereto, a pivoted cap feed 70 arm carried by said slide, a cam block for rocking said arm on its pivot, a spring normally holding said block away from said arm, a cam shaft and a cam thereon, for actuating said slide and means connected to said cam block and to said slide to advance said slide and to cause said cam block to rock said feed arm upon its pivot.

27. In combination, a cap chute, a cap feed arm movably mounted relative to said chute, and a cap carrier detachably mounted upon said arm for automatic disengagement therefrom in the event of misplacement of a cap.

28. In combination, a cap chute, a cap 85 feed arm movably mounted relative to said chute, a cap carrier sleeved about the free end of said arm for automatic disengagement therefrom in the event of misplacement of a cap, and a spring interposed between 90 said arm and said cap carrier.

29. In combination, a longitudinally reciprocable crosshead, a pair of can dies carried thereby and slidably transversely of the crosshead in their opening and closing 95 movements, a pair of pivoted rockers for opening and closing said dies, and an automatic lock for said crosshead applied and removed in the opening and closing movements of the dies, and comprising a spring 100 tensioned arm adapted for locking engagement with the crosshead, and a bell crank lever operated by said rockers in their opening and closing movements and adapted to actuate said locking arm.

30. In combination, a longitudinally reciprocable crosshead, a pair of can dies carried thereby and slidably transversely of the crosshead in their opening and closing movements, and an automatic lock for said cross- 110 head applied and removed in the opening and closing movements of the dies, and comprising a spring tensioned arm adapted for locking engagement with the crosshead, and a bell crank lever operated by said dies in 115 their opening and closing movements and adapted to actuate said locking arm.

31. In combination, a cap chute, a cap feed arm movably mounted relative thereto, a cap carrier mounted upon said arm and a 120 connection between said cap carrier and said cap feed arm permitting said carrier to automatically detach itself bodily from said arm in the event of misplacement of a cap.

32. In combination, a cap chute, a cap 125 feed arm movably mounted relative thereto, and a cap carrier shaped to carry thereon a surmounting cap and a connection between said cap carrier and said cap feed arm permitting said carrier to automatically bodily 130

detach itself from said arm in the event of misplacement of a cap.

33. In combination, a cap chute, a cap feed arm movably mounted relative thereto, a cap carrier mounted upon said arm and a connection between said cap carrier and said cap feed arm permitting said carrier to automatically detach itself bodily from said arm without interruption of the feeding movement of said arm in the event of misplacement of a cap.

34. In combination, a cap chute, a cap feed arm pivotally and slidably mounted relative thereto, means to slide said arm, means effective to the end of the sliding travel of said arm to rock said arm on its pivot, and a cap carrier mounted upon said arm and automatically bodily detachable therefrom without interruption of the feeding movement of said arm in the event of misplacement of a cap.

35. In combination, a can passageway, a pair of can dies movable towards and away from each other to grip and release a can disposed therebetween, a pair of cap dies operatively connected with said can dies to follow the opening and closing movements thereof whereby to close about and positively clamp a cap therebetween upon the closing movement thereof and to open and discharge said cap onto a can held between said can dies upon the opening movement thereof and having an independent phase of movement relative to said can dies effective to progressively and continuously work the cap across the can mouth from one side to the other until the cap is snugly seated entirely over said mouth.

36. In combination a can passageway, a pair of can dies slidable towards and away from each other to grip and release a can disposed therebetween, a pair of slidably and pivotally mounted cap dies operatively

connected with said can dies to follow the opening and closing movements thereof whereby to close about and positively clamp a cap therebetween upon the closing movement thereof and to open and discharge said cap onto a can held between said can dies upon the opening movement thereof, the pivotal connections for said cap dies permitting said cap dies an independent phase of movement arcually relative to said can dies effective to progressively and continuously work the cap across the can mouth from one side to the other until the cap is snugly seated entirely over said mouth.

37. In combination, a can passageway, a cap delivery, a cap release finger adapted to be entered into and withdrawn from the path of the caps, a lever disposed in the path of the cans for actuation thereby, and an operative connection between said lever and said finger.

38. In combination, a cap carrier, a cap feed arm pivotally and slidably mounted relative thereto, means to slide said arm, and means effective at the end of sliding travel of the arm to rock said arm on its pivot.

39. In combination, a longitudinally reciprocable crosshead, a pair of can dies carried thereby and slidable transversely of the crosshead in their opening and closing movements, a pair of pivoted rockers for opening and closing said dies, and an automatic lock for said crosshead applied and removed in the opening and closing movements of the dies.

In testimony whereof I affix my signature in presence of two witnesses.

SAMUEL B. FIELD.
